(57) **CLAIM**

The ornamental design for a surgical saw blade, as shown and described.

DESCRIPTION

FIG. 1 is a perspective view of a surgical saw blade; FIG. 2 is a top view thereof; FIG. 3 is a bottom view thereof; FIG. 4 is a first side view thereof; FIG. 5 is a second side view thereof; FIG. 6 is a first end view thereof; and, FIG. 7 is a second end view thereof.

The broken lines shown in FIGS. 1-7 illustrate portions of the surgical saw blade that form no part of the claimed design.

The dash dot lines shown in FIGS. 1-5 and FIG. 7 illustrates a boundary line that forms no part of the claimed design.
